UNITED STATES PATENT OFFICE.

CHARLES J. SIBBALD, JOHN O. SIBBALD, AND CHARLES T. A. SIBBALD, OF TROY,
NEW YORK.

SEWING MACHINE.

Application filed April 21, 1922. Serial No. 555,925.

To all whom it may concern:

Be it known that we, CHARLES J. SIBBALD, JOHN O. SIBBALD, and CHARLES T. A. SIBBALD, citizens of the United States, residing at Troy, in the county of Rensselaer and State of New York, have invented certain new and useful Improvements in Sewing Machines, of which the following is a specification.

10 This invention relates generally to an improvement in sewing machines, and particularly to an attachment designed for such cooperative working relation to an ordinary machine, that thereby the sewing machine 15 is adapted to stitch, in a predetermined cycle of operation, a letter, groups of letters, or a word or words, as may be required.

The present invention is particularly 20 characterized by and as a result of the fact that the means of the invention by which the particular stitching result is attained, is purely an attachment for the sewing machine, that is, it is wholly separate and independent 25 of the sewing machine mechanism, with the full capability of being readily and conveniently connected to or disconnected from the sewing machine. It is however essential that there be means provided on the attachment to control the stitching mechanism 30 so that when a name, letter or design is completed, the stitching mechanism will be automatically stopped, irrespective of the length of the name, letter or design, said 35 means being employed to prevent overrun of the stitches.

The improved attachment consists essentially in a cloth clamp in which the fabric to be operated upon is secured, and means, 40 such as independent cams, arranged to effect independent elements, with the component of the motion of such elements transmitted to the cloth clamp. Obviously therefore, the movement of the cloth clamp, and 45 therefore of the material in its presentation to the needle for the stitching operation, may be governed at will thru the particular cam formations provided, and hence the fabric may be moved in a single cycle of operation to cause the needle to stitch or outline therein a letter, group of letters, design, or a word, dependent entirely upon the cam formation.

As the attachment is primarily designed 55 to stitch the trade name of a manufacturer

in fabric articles, and as such names are frequently long, it is necessary to provide lengthy and quite deep cam surfaces to effect the stitching result. This necessity correspondingly involves long leverage and 60 to insure proper compensation of this leverage between the cams and the actuating levers we have provided specially designed means for transmitting the motion from the cams to the levers, which results in the 65 reduction to a minimum of lost motion and accurate stitching.

The invention further comprehends improvements in the details of construction and arrangement of parts which will be 70 hereinafter described and particularly pointed out in the claims.

The invention is illustrated in the accompanying drawings, in which:

Figure 1 is a perspective view of the attachment as applied to the sewing machine.

Figure 2 is an end elevation, parts being omitted in the rear to clearly illustrate the invention.

Figure 3 is a detail plan view of the cam element and associated parts, the standard of the sewing machine being in section.

Figure 4 is a detail perspective view of the means employed to impart intermittent motion to the cloth clamp.

Figure 5 is a detail perspective view of the manually operated clutch resetting means.

Figure 6 is a detail perspective view of the reverse side of the pulley of the resetting means shown in Figure 5.

The improved attachment comprises a material clamp including a lower member 1, which is adapted to rest squarely on and be freely movable with respect to the bed plate 2 of the sewing machine, which latter is indicated generally at 3. An upper or movable member 4 cooperates with the lower member 1 of the clamp, said upper member being pivotally connected at 5 to the lower member, and held in clamping relation to the latter thru spring 6. Means are provided to permit operation of the upper clamping member by suitable treadle connections when necessary to insert or withdraw material into or from the clamp. Both clamping members are formed at their free ends with enlarged portions 8 having interior openings, 9 of sufficient area to permit the full desired movement of the ma- 100
105
110

terial without interfering with the stitching movement of the needle 10 thru said openings.

Extending longitudinally from the lower cloth clamp member 1, is a bar 11, and on its under side, remote from the clamping end it is provided with a block 12. This block is mounted in transverse guideways 13, on a block 14, which is formed at opposite ends with gibbs 15, mounted to slide in fixed guideways 16, arranged at right angles to the guideways 13. Extending upwardly from the bar 11, are ears 17, to the upper ends of which the pivotal connection 5 is formed, for the upper clamp member 4. Rising from the free end of the upper clamp member are ears 18, between which is pivoted a lever 19. Pivoted intermediate the ends of this lever is a supporting link 20, the lower end thereof being pivoted at 21, to the bar 11. To the inner end of the lever 19, is attached the clamp lifting means, which comprises a flexible connection 22, connected to one end of a pivoted lever 23, 25 to the opposite end of which is pivoted a rod 23^a, which leads to a foot pedal (not shown).

A rock shaft 25, is supported in uprights 26, rising from the attachment base, and depending from this shaft is a finger 27, the lower end of which engages the end of an extension 28, attached to the block 12, a spring 29, attached to said finger and block, serving to maintain contact between the edge of the finger and the end of the extension. Extending from the shaft 25, is a lever 31, whose movement is controlled by a cam element 42. Suspended from the lever 31, by a spring 32, is a weight 33, to maintain said lever in intimate relation with the cam element and thereby impart accurate movement to the block 12. The sudden movements frequently imparted to the lever by abrupt cam surfaces renders it practically necessary to lend to the weight a certain amount of resiliency to insure accuracy in transmitting the motion from the cam surfaces to the cloth clamp, and we have therefore discovered that this condition can be successfully met by suspending the weight on a spring as shown.

Extending longitudinally from the block 14, is a bar 35, the free outer end of which engages the edge of a cam lever 36, pivoted to the attachment base at 37, and having one end so disposed as to be actuated by a series of cam surfaces, which will be hereinafter described. A coiled spring 38, attached at one end to the block 14, and at its opposite end to a stud on the attachment base, acts to move the block, and the parts it carries in a direction opposite to that imparted by the action of the cam surfaces.

65 Mounted in a bearing in the attachment

base, and extending above the same is a vertical shaft 40, provided at its lower end with a worm gear 41. On the upper portion of this shaft is mounted the cam member 42, provided with a vertical annular flange or drum portion 43, and a bottom horizontal flange 44. The edge of the drum portion 43 is provided with a plurality of definitely arranged and predetermined cam surfaces 45 to actuate the cam lever 31, while the edge of the flange 44, is provided with cam surfaces 46, to engage and actuate the cam lever 36. Adjacent the cam member 42, is a vertical guideway 47, in which slides a block 48, having a projecting roller 49, arranged to be in the path of movement of the cam surfaces 45. The cam surfaces 45 and 46, are so cut as to actuate the two cam levers in a manner that the composite action will move the cloth clamp under the needle to stitch in the fabric a predetermined letter, word or design, as will appear later on in the description of the operation of the machine.

Supported in bearings depending from the attachment base, is a shaft 50, carrying a worm 50^b, which meshes with the worm gear 41, on the cam carrying shaft 40. On the end of the shaft 50, is a loose pulley 52, and a fast disk 53. Also mounted fast on the shaft is a ratchet wheel 54, and on opposite sides of the same and swingingly mounted on the shaft is a yoke 55, and between the free ends of the same is pivoted a spring actuated pawl 56 normally in engagement with the ratchet teeth to rotate the shaft 50. Connected to the yoke 55, is a link 57 which is pivoted at its opposite end to a lever 58, depending from the usual oscillating shaft 59, employed in connection with the feeding means of the sewing machine, whereby to swing the yoke on its shaft to impart intermittent motion to the cam element. A hold back pawl 60, is pivoted to the attachment base and is adapted to prevent retrograde movement of the shaft.

A spring 61 is attached at one end to an arm depending from the base of the attachment and at its opposite end to a belt 62. The belt passes around the loose pulley 52, thence over an idler 63, then to a treadle (not shown). On one face of the loose pulley is a lug 64, adapted to contact with a fixed stop 65, on the frame, while on the opposite face of the pulley is a spring stop 66, which cooperates with a stud 67, projecting from the disk 53, toward pulley 52. In the depression of the treadle, the belt 62 is drawn upon, tensioning the spring 61, and the friction between said belt and the loose pulley rotates the latter and the outstanding end of the spring stop 66, picks up the lug 67 and rotates the shaft 50, until the lug 64 contacts with the fixed stop 65 on the machine, then when pressure on the pedal 130

is relieved, the reverse motion of the belt, correspondingly reverses the motion of the pulley until the lug 64, contacts with the opposite side of the fixed stop 65. The function of this particular mechanism is to enable the operator to manually operate the shaft 50, to return the cam element to a zero position after the usual stop motion has been brought into play and stopped the stitching mechanism. This is necessary where the letter or name stitched is not of sufficient length to cause a complete revolution of the cam element.

It is of the utmost importance that the stitching mechanism be stopped immediately the letter, name or design has been completed. Otherwise, additional stitches or tails would be formed on the work and would of necessity have to be subsequently removed, or second grade work would result. We have therefore provided means, with which the cam element cooperates, to actuate a stop motion mechanism exactly at the time of completion of the last stitch of the letter or word.

70 indicates a stop motion including the usual fast and loose pulleys 71 and 72, and 73 indicates a power belt. The belt passes thru an eye 73^a, in a lever 74 mounted on a vertical shaft 75. Secured to the shaft 75, is an adjustable catch 76 which cooperates with a latch 77, formed on the end of a lever 78, pivoted to the top of the attachment base at 79, the latch being drawn toward the catch by a spring 80. On the lever 78, is a lug 81, formed with a cam edge 82, and cooperating therewith is a cam lug 83, depending from the bottom of the cam element 42, the parts being so arranged that 40 when the lug 83, contacts with the cam edge 82, of the lug 81, the latch will be disengaged from the catch and the belt will be shifted to the loose pulley through the usual mechanism and the stop motion brought into play 45 to stop the stitching mechanism in the usual way.

In operation, a piece of fabric is placed between the jaws of the cloth clamp, and the upper clamp member is lowered. The stitching machine is tripped in the usual manner, which action actuates the catch 76, and its end engages the lever 78, and is caught behind the latch end to position the parts for automatically stopping the mechanism when a letter, name or other design is completed. The oscillation of the shaft 59 of the feeding mechanism, actuates the connections 58 and 57, which in turn rock the yoke 55, and thru the ratchet wheel 54, the shaft 50 is intermittently rotated. It may here be stated that the parts are so timed that the intermittent motion of the shaft 50, occurs at the time the needle is out of the fabric. Thru the worm 50^b and the worm gear 41, the cam element 42 is inter-

mittently rotated to impart to the cloth clamp the requisite movement to stitch the predetermined design in the fabric.

The cam surfaces 45 and 46, are formed so as to produce the necessary movement of the cloth clamp under the needle, to cause the latter to stitch a predetermined letter or name, it being understood that for each such predetermined letter or name a special cam element is required. The composite movement resulting from the two cam surfaces 75 results in the cloth clamp being moved in a path under the needle to produce curves and angles, consequently names may be stitched in goods in the form of signatures 80 to identify the manufacturer.

As the cam element rotates, the raised portions of the cam surfaces 45, through the vertical movement of the slide 48, and the upward movement of the lever 31, rocks the shaft 25, and consequently the finger 26, the movement of this finger toward the sewing machine head engaging the extension 28, and bodily moves the cloth clamp in the guideways 13, or in a transverse direction. 90 The depressed portions of the cam surface will, thru the weight 33, lower the lever 31, and because of the spring 29, cause a reversal of the transverse movement of the cloth clamp. It therefore follows that by the 95 action of the cam surfaces 45, and the connections described, transverse movement of the cloth clamp is controlled and made possible. The raised portions of the cam surfaces 46, act to rock the contact end of the 100 lever 36, outwardly, while its inner end is moved inwardly and against the bar 35, which results in the cloth clamp being moved longitudinally in the guideways 16, or at right angles to the movement imparted by the cam surfaces 45. The depressions in the cam surfaces 46, cause the spring 38, to retract the longitudinal movement of the cloth clamp in the guideways 16, so that the 105 entire longitudinal movement of the cloth clamp is controlled and made possible by the cam surfaces and the spring. 110

There is no permanent connection between the operative ends of the levers 31 and 36 with the cam surfaces, which is equally true 115 with reference to the contacts made between the lever 36 and bar 35, and the finger 26, and the extension. This arrangement permits free action with little binding friction between the parts, and in addition assures of accuracy in defining the movement of the fabric, which is important when imitating a name by stitching.

When the letter or name has been completed by the stitching operation, the lug 83, on the cam element 42, engages the cam lug 81 on the lever 78, and rocks the latter on its pivot 79, which disengages the latch end 125 from the catch 76, which thru the connections described releases the stop motion 130

mechanism and stops the stitching mechanism, hence the intermittent movement of the cam element ceases. It must be understood that the cam element may be stopped at any point in its revolution, the point of stopping depending entirely upon the length of the letter, name or design to be stitched. When the cam element is stopped it must be restored to a normal position and this we accomplish manually and wholly independent of the movement of the stitching mechanism. This movement is brought about by the operator depressing the pedal and tensioning the belt 62 which frictionally rotates the loose pulley 52 until the projecting end of the resilient stop 66, contacts with the lug 67 and rotates the disk 53, which of course rotates the shaft 50, and thru the gears the cam element 42. This movement is continued until the lug 64, encounters the fixed stop 65, which determines the normal or zero position of the cam element. When the cam element is returned to normal position, the operator removes pressure on the pedal, and the spring 61 returns the belt, consequently the pulley 52, to normal position, the pawls 56 and 60 holding the ratchet 54 in position.

The rod 23^a is connected to the pedal 30 which operates the loose pulley 52, and the length of the flexible connection 22 is such that it will not operate the cloth clamp until after the loose pulley has been rotated sufficiently to bring the cam element to normal position, so that if it be desired to stitch over the same letter or name to cure a defective stitch such operation can be performed without lifting the cloth clamp. The cloth clamp may however be automatically lifted when the stitching operation is completed by placing a trip 90 automatically operated by the mechanism of the sewing machine after a predetermined interval, under the lever 23.

From the foregoing description it is apparent that the material clamp and therefore the material will be moved as a result of the formation of the cam surfaces, the component of the cam movements thus directing the material along predetermined lines beneath the needle, so that the usual stitching movement of the latter will form in the fabric the desired letter, group of letters, word or words. To render the improvement of commercial value, it is of course obvious that its main use is in applying to fabric articles of manufacture, say for example collars, a particular letter, group of letters, or words, denoting for example the name or trade mark of the manufacturer. In such a use, which it is evident is only one of many, it will be appreciated that such letter, group of letters, word or words, must be completely formed at each cycle of operation; that following such cycle of operation

the sewing machine must be stopped; and the cam or other material clamp control must be brought to an initial or starting position; so that the machine is capable of repeating the letter, group of letters, word or words, in the successive fabric articles presented to it with the minimum loss of time between each cycle of operation and the minimum requirement on the part of the operator as to any adjustment or manipulation of parts.

Where circular or cylindrical cams are used, as in the present construction, the large number of stitches required necessarily limits the angular distance between stitch points to from one to two degrees, while the greatest distance in height between any two adjacent stitch points on either cam, depends upon the lever ratio between the cam and material clamp. If the levers are so pivoted as to move the clamp by the full amount of rise or fall in the cam between stitch points, any error in the cam is reproduced in full at the clamp, and if the rise or fall in the cam is slight, any lost motion in the parts between the cam and the clamp will absorb this slight movement before it reaches and effects the clamp. However, as is incident to the present construction, the levers may be so pivoted as to decrease the motion imparted by the cam with respect to the clamp, thus decreasing the effect of any possible cam error. However, this arrangement requires that the rise and fall on the cam must be greater than in other lever mountings, and as the linear distance between the stitch points on the cam must remain the same, the rises and falls of the cam must be steeper. As the levers are pivoted, the cam engaging end, if directly engaging the cam, must move in the arc of a circle. Therefore unless successive stitch points are of the same height, imperfect cam operation would result. That is to say, if the lever is mounted for pivotal movement and its free end operated directly by the cam, the maximum horizontal distance between the free end of the lever and its pivotal point is when the lever is exactly horizontal, and when the lever swings above and below this horizontal plane, the linear horizontal distance between the pivot point of the lever and that point at which the lever engages the cam, is shortened. Thus the cam engaging end of the lever cannot exactly follow the cam with true accuracy of lever movement due to cam alone, thus resulting in error. This error naturally increases with the increase in the total rise and fall of the cam and as naturally decreases as the distance between the lever pivot and the cam engaging end of the lever is increased. This difficulty has been reduced to a material extent by operating the lever at the cam end thru the block working in guides and operated by the cam

and in turn operating the lever. Thus the lever operating means from the cam moves in a straight line. Of course it will be understood that as the lever 31 rises and falls through movement of the block engaging the cam, the effective length of the lever 31 is continually varied, that is, lengthened above and below the true horizontal position of the lever, but this variation is effectively compensated for by corresponding variation in the effective length of the finger 27 engaging the end of the extension 28.

The important features of the present invention reside in having the clamp moving mechanism as an attachment, that is, entirely separate from the sewing machine, to thereby permit the use of comparatively enlarged cams and levers of suitable length and appropriately pivoted without regard to the construction of sewing machine used. Furthermore, in arranging the levers to decrease the amount of motion between the cam and the clamp, the cam error is thereby decreased. In having the carriage or cloth clamp so mounted, that the material may be brought close to the throat plate of the machine; in providing a stop motion for the machine and combined in operation therewith a means for subsequently bringing the cams to an initial or starting position; and in providing for the complete mechanical operation of the structure as a whole, for the automatic stitching of letters, groups of letters, word or words, the present construction presents an arrangement of commercial practicability.

It frequently happens that a trade mark includes more than one word, and in order to take care of this situation and form the proper space between the words, and to avoid stitching between the words, the cam element is provided with an additional lug to stop the sewing mechanism at the completion of the first word. The operator then manually moves the cam element to move the fabric to form the space, and then the sewing mechanism is again started to stitch the next word.

Claims:

1. The combination with a sewing machine of an attachment therefor to permit stitching of letters, words, characters, or the like, said attachment including a material holder to present the material to the stitching mechanism of the sewing machine, a cam for controlling the movement of said holder, a sewing machine stop motion controlled in and by the movement of the cam, and manually operable means independent of the stitching mechanism to move said cam to a normal starting position following the action of the stop motion.

2. The combination with a sewing machine of an attachment therefor to permit stitching of letters, words, characters, or the

like, said attachment including a material holder to present the material to the stitching mechanism of the sewing machine, a cam for controlling the movement of said holder, a sewing machine stop motion controlled in and by the movement of the cam, and means operative to move the cam to a predetermined relation to the stitching mechanism independently of the stop motion action.

3. The combination with a sewing machine of an attachment therefor to permit stitching of letters, words, characters, or the like, said attachment including a material holder to present material to the stitching mechanism of the sewing machine, a cam intermittently operated by the sewing machine for controlling the movement of said holder, a sewing machine stop motion controlled in and by the movement of the cam, and independent means for selectively continuing the intermittent motion of the cam following the action of the stop motion.

4. The combination with a sewing machine of an attachment therefor to permit stitching of letters, words, characters, or the like, said attachment including a material holder to present the material to the stitching mechanism of the sewing machine, a cam for controlling the movement of said holder, means for feeding the cam in a step-by-step movement in the operation of the sewing machine, and a sewing machine stop motion controlled in and by the independent movement of the cam, said cam being free of the feeding means whereby to permit manual movement of the cam, independently of the operation of the feeding means, following the action of the stop motion.

5. The combination with a sewing machine of an attachment therefor to permit stitching of letters, words, characters, or the like, said attachment including a material holder to present the material to the stitching mechanism, a cam for controlling the movement of said holder, means for feeding the cam in a step-by-step movement in the operation of the sewing machine, a sewing machine stop motion controlled in and by the movement of the cam, whereby to arrest the stitching at a predetermined point, and manually operable means to further operate the cam to a predetermined position without affecting the stitching mechanism.

6. The combination with a sewing machine of an attachment therefor to permit stitching of letters, words, characters, or the like, said attachment including a material holder to present the material to the stitching mechanism of the sewing machine, a cam for controlling the movement of said holder, means for feeding the cam in a step-by-step movement in the operation of the sewing ma-

chine, a sewing machine stop motion controlled in and by the movement of the cam, whereby to arrest the stitching at a predetermined point, and manually operable cam 5 positioning means adapted for actuation following the action of the stop motion and independently of the sewing machine.

7. The combination with a sewing machine, of an attachment therefor including 10 a material holder to present the material to the stitching mechanism of the sewing machine, a cam normally free of the sewing machine for controlling the movement of the holder, step-by-step cam feeding means operated by the sewing machine, means operated by the cam to limit actuation of the stitching mechanism at a predetermined point in the cam movement, and manual means for operating the cam beyond said 15 predetermined point to position the cam at a normal starting point independently of the stitching mechanism.

8. The combination with a sewing machine, of an attachment therefor including a 25 material holder to present the material to the stitching mechanism of the sewing machine, a cam, means intermediate the cam and holder to operate the latter in accordance with the cam formation, a stop motion for the 30 sewing machine, means on the cam to actuate the stop motion in a predetermined position of the cam, manually operable means to move the cam independent of the stitching mechanism and following the action 35 of the stop motion, and means to limit such independent movement of the cam to the normal starting position thereof for the next stitching operation.

9. The combination with a sewing machine, of an attachment therefor including 40 a material holder to present the material to the stitching mechanism of the sewing machine, a plural cam, means intermediate the cam and holder to operate the latter in accordance with the composite cam formation, a stop motion for the sewing machine, means on the cam to actuate the stop motion in a predetermined position of the plural cam, manually operable means to move the 45 plural cam independent of the stitching mechanism and following the action of the stop motion, and means to limit such independent movement of the plural cam to the normal starting position thereof for the next stitching operation.

10. The combination with a sewing machine, of an attachment therefor including a material holder to present the material to the stitching mechanism of the sewing machine, a cam, means intermediate the cam and holder to operate the latter in accordance with the cam formation, means intermediate the sewing machine and cam to impart a step-by-step movement to the cam in

the operation of the sewing machine, means 65 for stopping the sewing machine mechanism when the cam has reached a predetermined point, a normal-position locator for the cam, and means for manually adjusting the cam with regard to said locator independently of 70 the sewing machine mechanism.

11. The combination with a sewing machine, of an attachment therefor including a material holder to present the material to the stitching mechanism of the sewing machine, 75 a cam, means intermediate the cam and holder to operate the latter in accordance with the cam formation, a shaft, means intermediate the shaft and cam for operating the latter in the movement of the shaft, means operated by the sewing machine for actuating the shaft, a stop motion for the sewing machine operated by the cam, and means for independently operating the shaft following 80 the action of the stop motion to advance the 85 cam to a normal starting position without affecting the stitching mechanism.

12. The combination with a sewing machine, of an attachment therefor including a material holder to present the material to 90 the stitching mechanism of the sewing machine, a cam, means intermediate the cam and holder to operate the latter in accordance with the cam formation, a shaft, a 95 ratchet wheel secured on the shaft, means operated by the sewing machine for imparting a step-by-step movement to the ratchet wheel, a stop motion for the sewing machine mechanism controlled in the movement of the cam, a limiting stop adjacent the shaft, 100 a stop cooperating member loosely mounted on the shaft, manual means for actuating 105 said member, and means whereby said member in actuation engages and operates the shaft to a position determined by said limiting stop and stop cooperating member, 110 whereby to operate the cam to a normal starting position following the action of the stop motion.

13. A letter writing attachment for sewing machines, including plural cam members to be actuated by the sewing machine, a material holder including clamping members, a block on which said holder is secured, a guide in which said block is slidable, a second guide in which the first-mentioned guide is slidable, means controlled by one cam member to adjust the first-mentioned guide in the second guide, and means 115 cooperating with the other cam member to 120 adjust the block in the first-mentioned guide, said latter means including a lever connected with the block, an arm for operating the lever, a support adjacent the plural cam member, a member slidable in the support and operating the arm, and means carried by the last-mentioned member to engage 125 the said other cam member, and means for

operating the plural cam member as a unit to thereby operate the material holder with composite cam control.

14. The combination with a sewing machine having stitching mechanism, of an attachment therefor including a material holder to present the material to the stitching mechanism, a cam for controlling the movement of said holder, a sewing machine stop motion, a plurality of means on the cam for successively operating the stop motion at successive periods of cam movement within a complete cycle of cam movement, and means for manually advancing the cam following any action of the stop motion to advance the cam to a fresh starting position and simultaneously operate the holder to provide a determinate spacing of the material between the final stitching determined by the stop motion and the initial stitching following the stop motion, whereby to provide for the proper spacing of a plurality of words, letters, characters, or the like, making up a single cam cycle of operation.

15. The combination with a sewing machine having stitching mechanism, of an attachment therefor including a material holder to present the material to the stitching mechanism, a cam for controlling the movement of said holder, a sewing machine stop motion, a plurality of means on the cam for successively operating the stop motion at succeeding periods of cam movement within a complete cycle of cam movement, said material holder comprising clamping members adapted to be operated at will to release the material, and means

for manually advancing the cam a definite distance succeeding any stop motion action of the cam without releasing the material holder clamping action on the material, whereby in the event of imperfect stitching the manual operation of the cam in restoring the same to normal starting position will simultaneously position the material to normal starting position for an exact duplication in the material of the original stitching.

16. The combination with a sewing machine having a stitching mechanism, of an attachment therefor including a material clamp to present the material to the stitching mechanism, a cam for controlling the movement of the material clamp, a sewing machine stop motion, means for manually operating the clamp to release the material, and means to manually operate the cam following the action of the stop motion to advance the cam to a normal starting position, said means for manually operating the cam being capable of operation at will without effecting an operation of the clamp to release the material, whereby at will the material stitched in one operation of the clamp may be restored to initial starting position of such stitch simultaneously with the manual movement of the cam to normal starting position, to thereby restitch the previous stitched outline.

In testimony whereof, we affix our signatures.
